Charles Stanley Jacob INVENTOR

BY Frank J. Mautz, his ATTORNEY.

UNITED STATES PATENT OFFICE.

CHARLES STANLEY JACOB, OF ELIZABETH, NEW JERSEY.

SKETCHING-BOARD.

1,356,719.

Specification of Letters Patent. Patented Oct. 26, 1920.

Application filed October 22, 1918. Serial No. 259,183.

To all whom it may concern:

Be it known that I, CHARLES STANLEY JACOB, a citizen of the United States, residing at Elizabeth, in the county of Union and State of New Jersey, have invented certain new and useful Improvements in Sketching-Boards, of which the following is a specification, reference being had thereto in the accompanying drawings, which

10 form a part thereof.

My invention relates to a sketching board and more particularly to a board adapted for use in making rough sketches in military and general field work, and for use in giving instructions in the art of making sketches of this character.

A sketching board, made in accordance with my invention, embodies therein, in convenient form, all implements necessary 20 for the user to determine direction, position and slopes, and for accurately and rapidly indicating the same at the desired scale upon the drawing paper.

It is also so constructed as to be conveniently used in contour work, and for judging the altitude of different elevations, and in orientation, resection and intersection work.

With a board made in accordance with 30 my invention, proficiency in the rapid making of sketches may be readily acquired, and the maintenance of a proper scale throughout the sketch is greatly facilitated.

While, in the use of a board made in accordance with my invention, a practical knowledge of topographical drawing, landscape and reconnaissance sketching, and rough surveying work, is essential, the structural characteristics of this board are such 40 as to facilitate sufficiently accurate and rapid making of such sketches, and to keep readily at the hand of the user, all of the essential tools and implements and indicated data, for facilitating rapidity in the 45 exercise of this knowledge.

The invention consists in the novel features of construction and combination of parts hereinafter set forth, and described, and more particularly pointed out in the 50 claims hereto appended.

Referring to the drawings.

Figure 1 is a top view of a drawing board embodying my invention broken away in places; and

Fig. 2 is a vertical section thereof.

Like letters refer to like parts in both of said views.

In the embodiment of my invention shown in the drawings, α indicates a drawing board made of suitable material, such as clear-grained white pine, having adjacent the top thereof parallel slots a' — a^2 , having rotatably mounted therein parallel rollers b and c , adapted to receive and feed a strip of paper d . Each roller b and c is provided with an end disk as b' and c' , for turning said rollers, the peripheries of which have a sequence of grooves therein, coöperating with which respectively are pivotal lock-plates b^2 and c^2 , to hold the paper taut when making sketches, while permitting the free feeding of the paper from one roller to the other, when such is required.

The portion of the board between the slots a' — a^2 forms a suitable backing for the paper d , and adjacent said slots and along the edges of the space between them occupied by the paper, the board α has a sequence of graduations, facilitating the production of sketches to scale.

Adjacent the lower edge of the board is a segmental slot a^3 , the board along the inner arc of said segment having "slope" graduations for determining grades or slopes, and altitudes with a degree of precision suitable for the class of work for which the board is adapted to be used. Said board α , adjacent the top thereof and radially of the center of the segment a^3 , has an opening a^4 through which a plumb-line e passes, the plumb-bob e' carried by this line being adapted to enter and have movement in the segmental slot a^3 .

To permit the use of the board for contour work, it is desirable that means be provided whereby, in repeatedly sighting over the top of the board, it may always be positioned at the same distance from the eye. To meet this condition, I make the plumb-line e adjustable in length by placing a spring cleat f upon the back of the board by means of which the length of the line e may be adjusted, thus permitting the user, by holding the plumb-bob in his mouth, to maintain the board at the proper distance from the eye.

When the plumb-bob is not in use, it, together with its line, is stored in a socket a^5 .

in the edge of the board, adjacent the opening a^3 .

5 Pencils of different colors are required, particularly in military sketching, and in order to have such pencils conveniently accessible to the user, I provide a plurality of sockets in the edge of the board, adjacent the socket a^6 , adapted to receive pencils. All of these sockets are closed by means of a pivotal plate g .

10 Seated in a recess in the board a , adjacent the segmental slot a^3 , is a compass h secured in place by a cross bar h' having a sight h^2 coincident with the axis of the compass 15 needle. This sight is provided for the purpose of permitting the user to locate an object with relation to the magnetic north, as indicated by the compass. About the upper half of the compass, the board a is provided with protractor lines coinciding with 20 the degree lines of the compass, the edge of the board being provided with corresponding graduations.

15 Pivots and slidably mounted upon the board a by means of a wing bolt i' , is a slotted rule i having graduations along both edges thereof, the scale of which corresponds with the scale markings at the sides of the slots a' and a^2 . The axis of pivotal 25 movement of this rule is alined with the axis of the compass needle, and with the center graduations at the top and bottom of the portion of the board forming a backing for the paper. The slot in this rule extends 30 along the center line of the rule for a substantial portion of the length thereof, affording the proper strength of material at the opposite ends thereof.

35 Pivots and mounted upon the rule i is an extension rule j , the connection between these rules being by means of a slidable pivot screw fitting and its coöperating thumb nut j' . The rule j is also slotted in the same manner as the rule i , the screw fitting passing through, and the nut j' engaging the rule on opposite sides of this slot. Carried by the rule j is a small 45° triangle k , which is mounted upon said rule by means 45 of a suitable pivot screw fitting and thumb nut k' , so as to be adjustable thereon both lengthwise of the rule, and by a rotative movement, to bring the desired edge of the triangle into the proper relation with the rule, and the paper d .

50 Both rules are preferably made of flexible material, so as to permit the ends thereof to be moved away from the board, and passed over the retaining bolts $m-m'$, upon opposite sides of the wing bolt i .

55 In the opposite upper corners of the board are two sights $n-n'$, to be used in conjunction with the plumb-bob in approximating elevations.

60 Both edges of the rules i and j , and all 65 edges of the triangle k are provided with

graduations on the same scale as the graduations about the openings a' and a^2 , and the portion of the board between said openings.

The board may have indicated thereon, if desired, data as to the contour interval and 70 representative fraction scale, slope data, and a list of conventional sign names, this data being applied to any desired portion of the board. This is not indicated on the drawings, as it is merely a matter of convenience 75 and is not essential to the invention.

The various uses of a board made in accordance with my invention, will be apparent to anyone skilled in the line of work for which the board is particularly adapted, 80 and may be readily acquired by a student in this class of work.

When the board is not in use, the rule i is centered with relation to the wing bolt i' , and the ends thereof flexed and passed over 85 the retaining bolts $m-m'$. The rule j is then centered with relation to said bolt i' , slipped over the head thereof, and its ends are passed over the bolts $m-m'$, these bolts then being turned to hold the rules flat upon 90 the board.

When it is desired to use the board, the rules are released by a reversal of this operation.

In determining slopes, and in analogous 95 work, the plumb-bob e' is brought into the slot a^3 and the board is handled as with the ordinary slope board, the plumb-line e alining itself with one of the slope graduations within the arc of the opening a^3 , thus indicating the degree of the slope.

For altitude work, the sights $n-n'$ are used in securing a sight upon the desired object or location, the plumb-bob and line indicating the angular inclination of the 105 board from which the altitude may be calculated upon the basis of other available data.

The compass and its sight may be used in the usual manner in orientation, resection 110 and intersection work, as well as for determining directions in the making of sketches.

The rules i and j may be used as a T-square, the gage graduations about and adjacent the openings a' and a^2 facilitating the 115 truing up of this square. By reason of the pivotal support of the rule i and the pivotal slidable connection between same and the rule j , lines at any desired angle may be readily drawn, the protractor lines about 120 the compass, and at the edge of the board, permitting absolute accuracy in the locating of objects upon the map. The sight h^2 is also useful in this connection.

The triangle k may be brought to any position upon the rule j , and by reason of the graduations thereon, and upon said rule, the drawing may be readily kept to scale. The scale markings upon the rule i are particularly useful in securing a proper position 125 130

of the rule *j*, particularly in drawing in the horizon, and in contour work.

In landscape work, as heretofore stated, the plumb-line may be used in order to insure accuracy in the positioning of the board with relation to the eye of the user, thus permitting different locations to be accurately indicated upon the drawings by taking a succession of sights over the top edge 10 of the board, and a due observance of previously noted locations.

With a board made in accordance with my invention, accuracy of scale and rapidity of execution is greatly facilitated, which 15 is highly desirable in a board of this character, because the work required to be done must be accomplished, at times, under most trying and most difficult circumstances. Furthermore, clear, well defined sketches are 20 desirable, and the flexibility of the rules *i* and *j* by reason of their being pivotally and slidably supported in relation to the board, and each other, and by reason of the scale markings thereon, facilitates accuracy in the 25 making of the lines.

The rule *j* may be brought so as to make a vertical line upon any portion of the paper *d*, or a horizontal line on any portion thereof with the assistance of the graduations 30 about the openings *a'* and *a''*, and along the backing surface between said openings. It may also be brought, by a simultaneous pivotal and sliding movement of the rules *i* and *j*, with the pivot *j'* between the center 35 of the compass and the slot *a''*, into accurate alinement with any of the protractor lines about the compass, thus facilitating accuracy in the location of different objects upon the paper *d* when making a map for range finding 40 purposes, or for greater accuracy in the making of the map. As in other uses of the rules, the scale graduations thereon are also an important factor in thus locating objects upon the map being made.

The structure of the board is such as to make it capable for various other uses in the making of maps in military work and other rough field work, which will be apparent to those skilled in such work. The board may 50 be used upon a tripod, or be held by hand, as desired, or as occasion may require. It combines in one structure all of the implements necessary for use in the making of sketches of the character which it is designed to facilitate, and all these are associated with the board in a manner to prevent their being misplaced, or lost.

The board *a* may be made of any desired 60 dimensions, it being desirable to make the various metallic parts of a non-magnetic metal, so as to avoid interference with the compass.

It is not my intention to limit the invention to the precise details of construction 65 shown in the accompanying drawings, it

being apparent that such may be varied without departing from the spirit and scope of the invention.

Having described the invention, what I claim as new and desire to have protected 70 by Letters Patent, is:—

1. A sketching board embodying therein a portion adapted to serve as a backing for the paper, said portion having about all edges thereof scale graduations, a rule pivotally mounted upon said board, a second rule pivotally, and slidably mounted upon said first named rule, and a compass set into said board, said board having protractor lines about said compass and corresponding 75 graduations about the edge of the board, and said rules each having upon opposite edges thereof, graduations to scale.

2. A sketching board embodying therein a portion adapted to serve as a backing for 80 the paper, said portion having about all edges thereof scale graduations, a rule pivotally mounted upon said board, a second rule pivotally, and slidably mounted upon said first named rule, a compass set into 85 said board, said board having protractor lines about said compass and corresponding graduations about the edge of the board, and said rules each having upon opposite edges thereof, graduations to scale, and a 90 triangle rotatably and slidably mounted upon said last named rule.

3. A sketching board embodying therein a portion adapted to serve as a backing for 95 the paper, said portion having about all edges thereof scale graduations, a rule pivotally mounted upon said board, a second rule pivotally, and slidably mounted upon said first named rule, a compass set into 100 said board, said board having protractor lines about said compass and corresponding 105 graduations about the edge of the board, and said rules each having upon opposite edges thereof, graduations to scale, a cross bar holding said compass in position, and 110 a sight carried by said cross bar concentric with the axis of the compass needle.

4. A sketching board embodying therein a portion adapted to serve as a backing for 115 the paper, said portion having about all edges thereof scale graduations, a rule pivotally mounted upon said board, a second rule pivotally, and slidably mounted upon said first named rule, a compass set into 120 said board, said board having protractor lines about said compass and corresponding 125 graduations about the edge of the board, and said rules each having upon opposite edges thereof, graduations to scale, and headed screw bolts arranged at opposite sides of the point of pivotal support of said first named rule, said rules being of flexible material, and having slots therein through which said bolts may pass.

5. A sketching board embodying therein 130

2
a portion having slots adjacent the opposite sides thereof, forming a backing for the paper, intermediate said slots, parallel rollers mounted in said slots adapted to hold and feed a paper strip, the board adjacent said slots and said backing portion having scale graduations thereon, means whereby said rollers may be locked against movement, a rule pivotally mounted upon 10 said board, a second rule pivotally, and slidably mounted upon said first named rule, and a compass set into said board, said board having protractor lines about said compass and corresponding graduations 15 about the edge of the board, and said rules each having upon opposite edges thereof, graduations to scale.

6. A sketching board embodying therein a portion adapted to serve as a backing for 20 paper, said portion having about all edges thereof scale graduations, a rule having a slot therein for a substantial part of the length thereof, means seated in said slot

pivotal and slidably connecting said rule with the board, a second rule also having 25 a slot therein for a substantial portion of the length thereof, a fitting mounted in the slots of said rules respectively, whereby said last named rule is pivotally and slidably connected with said first named rule, a compass set into said board, said board having protractor lines about said compass and corresponding graduations about the edge of the board, and said rules each having upon 30 opposite edges thereof, graduations to scale, 35 and a triangle rotatably and slidably mounted upon said last named rule.

In witness whereof I have hereunto affixed my signature, this 11th day of October, 1918, in the presence of two subscribing 40 witnesses.

CHARLES STANLEY JACOB.
